INVENTOR.

Robert Lee Wright

UNITED STATES PATENT OFFICE.

ROBERT LEE WRIGHT, OF LOS ANGELES, CALIFORNIA; WILLIE CROCKETT WRIGHT
ADMINISTRATOR OF SAID ROBERT LEE WRIGHT, DECEASED.

AIRCRAFT.

Application filed July 28, 1923. Serial No. 653,263.

This invention relates to airplanes and other aircraft and represents an improvement in part of my following co-pending applications,—

5 Application filed March 7th, 1918, Serial No. 221,005, application filed December 30th, 1922, Serial No. 610,036, and application filed April 25th, 1923, Serial No. 634,504.

With these and other objects in view the 10 inventions consist in the novel details of construction and combination of parts more fully hereafter disclosed and particularly pointed out in the claims.

Referring to the accompanying drawings 15 forming a part of this specification in which like numerals designate like parts in all the views.

Figure 1 is a top plan view of a combined land and water craft;

20 Figure 2 shows a side elevation thereof partly broken away and illustrated in section;

Figure 3, illustrates the propelling means therefor;

25 Figure 4, illustrates a side view of a combined air, land and water craft partly broken away and shown in section;

Figure 5 is a detailed sectional view taken through the forward end of the craft shown in Figure 3;

30 Figure 6 illustrates a view in perspective of the operating means for the forward wing of said craft;

Figure 7 is a fragmentary plan view of 35 portions of the propelling and steering means; and

Figure 8 is a plan view of the propellers and driving means therefor.

My invention in the form or embodiment shown in the drawings and briefly described, 40 comprises a water craft 1, having a deck 2, an outer bottom 3, and sides and ends of the outer bottom of said ship indicated at 4. The inner bottom of the ship which is shown at 5 is provided with sides and ends indicated at 45 6. A space 7 is formed between the outer and inner bottoms of the ship.

Vertically mounted tubes or boxings 8 are disposed between the inner and outer bottoms of the ship and are provided with

50 springs 9. Shafts or projections 10 are secured to the inner bottom 5 of the ship and are provided with slightly enlarged head portions at their lower ends for the purpose of resting upon the coil springs 9. Oil grooves or channels 11 may be located in the

projections 10 and leads to the bottom 12 in any desired manner. Oil tubes 13 are arranged between the oil openings 11 and the oil supply pipes.

Bolts 15 are secured to the outer bottom 3 60 of the ship and are extended at their upper ends through openings 16 located in the inner bottom 5 and are held in their upper position by means of the bolt heads 16^a. In this manner the springs 9 may readily respond to 65 the load and pressure of the passengers and cargo on the ship.

A rod 17 is secured to the inner bottom 5 and is provided with electric contacting means 18 on the lower end thereof which are 70 provided with contacting pins 19. Wires 20 connect the contacting pins, 19 with a suitable bell or indicator (not shown) for the purpose of resiliently mounting the rod 17 within its support 17^a. I locate at the upper 75 end of the rod a coil spring 17^b. An electric contact plate 21 is secured to the outer bottom 3 and adapted for engagement by the pins 19 to which are attached wires 22 that lead to an electric bell or other indicator 80 (not shown).

The front of the ship is provided with a forwardly extending projection 26 for the purpose of providing a support for a steering member or projection 27. A shaft 25 is 85 vertically mounted in the forward end of the projection 26 for pivotally supporting the steering member 27.

The rearward portion of the steering member 27 is formed substantially arcuate and is 90 provided at its upper end with a rack 29 and is adapted to be engaged by a pinion 31 which is secured to one end of the shaft 30. Secured to the opposite end of the shaft 30 is a beveled gear 32 which meshes with a 95 similar gear 33 mounted upon the upper end of the vertical shaft 34. In this manner the steering member 27 may be readily turned by any suitable electric motor through the medium of clutches or similar devices. The extreme point 35 of the steering member 27 is 100 so formed as to permit the ship's passage through the water with a minimum amount of resistance.

Outwardly extending propellers 120 are 105 provided on the ground wheels 123 for the purpose of moving the craft through the water. These spirally formed propellers may of course be removed from the hubs of the wheels while traveling on land. For the 110

purpose of driving this device a shaft 101 is provided with gears 99 and 100 to which suitable power is connected such as a motor or the like.

- 5 A shaft, 110, similar to the shaft, 101, is provided for steering the craft and is provided on its upper end with a pair of gears, 109, and 111, which may be attached to any steering mechanism as desired. The lower 10 end of the steering shaft, 110, is provided with a bevel gear 116, and is adapted to mesh with the cogs, 112, of the gear segment 113. The gear 116, is integrally formed to the upper end of the stub shaft 114, whereas the 15 lower end of the stub shaft is integrally connected to the axle 115. In Figure 7 a portion of the axle is indicated as at 118 which is provided at each of its ends with the usual pivotal joints, 119.
- 20 In the embodiment of my invention illustrated in Figures 3, 4, 5 and 6 I illustrate a craft which may be used as an aeroplane, automobile, or boat as desired. A greater portion of the construction of this embodiment of my invention having been already described, reference will be hereinafter made to those details which are distinct from the others.

25 A wing, 125, which is of course located upon the upper side of the deck, 124, is of the usual well known construction and is secured to the deck by means of braces 126.

30 This particular craft is also provided with a wing, 132, which is located at the forward end thereof and a relatively short distance above the front portion, 27^a. This wing, 132, is held in position by means of a pair of vertically extending shaft portions, 145, which are adapted to slide within the cylinders, 148, which are in turn securely mounted upon the 35 upper surface of that portion of the craft.

35 A segmental gear, 134, is suitably fastened to the side of the wing, 132, and is provided with gear teeth, 135. A shaft, 136, is provided with a gear, 137, which is adapted to mesh with the teeth 135, of the segment 134. The shaft, 136, is in turn actuated by means 40 of the shaft 129 in connection with mating bevel gears 138, and 139, as clearly shown in Figure 6 of the accompanying drawing.

45 On the opposite end of the shaft, 129, to the gear 138, is mounted a bevel gear 130, which is adapted to mesh with a mating gear 128 for the purpose of rotating the wing, 50 132. Any suitable power may of course be applied to the shaft on which the gear, 128, is fastened.

55 A rackbar, 150, is secured to the lower end of one of the shafts, 145, and is adapted to be 60 engaged by a pinion, 151 which is secured to one end of the horizontally extending shaft, 152, as clearly shown in Figure 6. A bevel gear, 155 is securely mounted on the opposite end of the shaft, 152 and is likewise as gear 65 128 adapted to be rotated by any suitable

mechanism. The rotation of the shaft, 152, will cause the raising or lowering of the vertically extending shaft, 145, for tilting the wing, 132.

70 A projection, 142, is secured to the lower side of the wing, 132, for the purpose of mounting the wing upon the shaft, 141. Suitable collars, 143, are secured around the shaft, 141, and located on each end of the projection 142. A pin, 153, is horizontally extended 75 through the upper end of the rod or bar, 145 and is adapted to be engaged by a pair of forks which are integrally formed upon each end of the shaft, 141. The forked arms it will be noted extend on either side of the shaft, 80 145. Universal couplings, 140, are placed upon each of the shafts, 129, and 152.

85 On the forward end of the projection, 35, is provided an air propeller, 157, preferably having two oppositely disposed plates and 90 is preferably mounted to rotate by means of a shaft, 159, which of course extends rearwardly into the craft where it is driven by any suitable motor. Centrally mounted with respect to the air propeller 157, is an outwardly extending and substantially conical member 158, for the purpose of effectually steering the craft when in the water. This spiral member is preferably formed of plates or 95 fans, 165.

100 A universal joint, 160, is located at a convenient point on the shaft, 159, as is clearly indicated in Figure 5 of the accompanying drawings.

105 With particular reference to Figure 8 of the accompanying drawings which illustrates a somewhat diagrammatic view of the various driven shafts and the means of propulsion, it will be noted that the line shaft, 159, is provided with a plurality of bevel gears, 168 which are adapted to mesh with the oppositely disposed mating gears, 167, which are in turn secured to the inner ends of the cross-shafts, 166. The bearings, 171, which are diagrammatically shown are preferably located 110 near the outer end of the cross-shafts, 166.

115 I employ a pair of motors of any desired or well known type, 176, and 177, and are so connected that in case one should need adjustment or otherwise become out of order, the other one would serve the purpose of driving the entire mechanism. The motor, 177, is provided with the shafts, 178, on which are mounted the bevel gears, 181, for the purpose of driving the mating gears, 177 and 179. 120 The gears 179, are mounted upon the relatively short shafts, 180, which are keyed or otherwise secured to the bevel gears, 183. The gears 183, are of course mounted to mesh with similar gears which are keyed on to the 125 main drive shaft, 159. For the purpose of disengaging either one motor or the other the clutches, 185, are mounted upon either side of the engine or motor, 176.

130 Clutches, 174, may be suitably located upon

the various shafts for the purpose of disengaging any of the propellers when desired and are operated by means of the hand controlled levers, 175. In this manner various combinations of all propellers may be had.

What I claim is:—

1. An aircraft having a body carrying a plurality of supporting wheels operated on each side of said body, a spiral propeller with its rear end secured to each of said wheels, each of said spiral propellers extending straight out from each of said wheels, and means to operate said propellers when said wheels are rotated.
2. An aircraft having a body with a projection formed on the forward end of said body, a second projection operated on the forward end of said first mentioned projection, both of said projections extending straight forward from the forward end of said body, a propeller with its rear end formed on the forward end of a shaft extending out straight forward from the forward end of said second mentioned projection, said propeller sloping from its rear part to a point on its forward end, a plurality of motors geared to said shaft, and means to simultaneously and separately operate said plurality of motors, and rotate said shaft.
3. An aircraft having a body with a projection formed on the forward end of said body, said projection extending straight forward from the forward end of said body, a second projection operatively secured to said first mentioned projection, said second projection extending straight forward from the forward end of said body, a propeller with its exterior formed sloping from its rear part to a point on its forward end extending straight forward from the forward end of said second mentioned projection, the rear end of said propeller secured to the forward end of a shaft extending out from the forward end of said second mentioned projection, and a plurality of separate means to both simultaneously and separately rotate said shaft and operate said propeller.
4. An aircraft having a body with a projection formed on the forward end of said body, a second projection operated on said first mentioned projection, a screw propeller with its exterior sloping from its rear part to a point on its forward end with the rear part of said propeller secured to a shaft extending out from the forward end of said second mentioned projection, said second mentioned projection and propeller extending straight forward from the forward end

of said body, a plurality of motors geared to said shaft, and a plurality of separate means to both simultaneously and separately rotate said shaft and propeller, and means to turn said second mentioned projection and said propeller at a suitable angle to direct the course of said aircraft.

5. An aircraft having a body, a projection operated on the forward end of said body, a motor having a propelling shaft carried by said body, said propelling shaft extending straight forward from said motor through the forward end of said body and out through the forward end of said projection, said propelling shaft having a swivel joint formed in a way to permit said propelling shaft and said projection to be turned at any suitable angle to direct the course of said aircraft, the rear end of a propeller formed on the forward end of said propelling shaft in front of said projection, said propeller extending straight forward with its exterior sloping from its rear part to a point on its forward end, and an aircraft wing with a projection formed on its front mounted on said first mentioned projection.

6. An aircraft having a body with ground wheels rear and front, each of said wheels having a spiral propeller horizontally operated on the side of each of said wheels, each of said front wheels having a vertical shaft with pinion on its lower end operated on cogs or teeth forming a pinion on the inner part of each hub of said forward wheels, a second pinion secured to each vertical shaft above said pinion, each of said second pinions meshing with a pinion on a horizontal shaft with a pinion on the other end of each of said horizontal shafts meshing with cogs or teeth forming a pinion on the inner part of each of the hubs of each rear wheel, and any suitable motor or any suitable power geared to each of said vertical shafts to rotate said vertical shafts and cause all of said front and rear wheels to propel or pull simultaneously.

7. An aircraft comprising a body, ground wheels mounted upon each side thereof, a substantially conical and spirally formed propeller centrally mounted and outwardly extending with respect to each of said wheels, a pair of motors, a drive shaft, a plurality of driven shafts connected to said wheels and adapted to be geared to the drive shaft, and a plurality of clutches operatively arranged whereby power may be taken through either one motor or the other.

In testimony whereof I have hereto set my hand.

ROBERT LEE WRIGHT.

CERTIFICATE OF CORRECTION.

Patent No. 1,693,557.

Granted November 27, 1928, to

It is hereby certified that the above numbered patent was erroneously issued to "Robert Lee Wright, deceased, of Los Angeles, California, whose Administrator is Willie Crockett Wright", whereas said patent should have been issued to "Robert Lee Wright, deceased, of Los Angeles, California, whose Administratrix is Willie Crockett Wright", as shown by the records of assignments in this office; and that the said Letters Patent should be read with this correction therein that the same may conform to the record of the case in the Patent Office.

Signed and sealed this 8th day of January, A. D. 1929.

(Seal)

M. J. Moore,
Acting Commissioner of Patents.
